UNITED STATES PATENT OFFICE

138,898

DESIGN FOR A PORTABLE CRANE OR SIMILAR ARTICLE

Lad L. Hercik, Lakewood, Ohio, assignor to The
Hill Aeme Company, Cleveland, Ohio, a cor-
poration of Ohio

Application January 26, 1944, Serial No. 112,333

Term of patent 14 years

(Cl. D41—1)

To all whom it may concern:

Be it known that I, Lad L. Hercik, a citizen of the United States, residing in Lakewood, in the county of Cuyahoga and State of Ohio, have invented a new, original, and ornamental Design for Portable Cranes or Similar Articles, of which the following is a specification, reference being had to the accompanying drawings, forming a part thereof.

Fig. 1 is a perspective view of a portable crane embodying my new design and showing principally the left side of this crane.

Fig. 2 is a right side elevation of the portable crane illustrated in Fig. 1.

Fig. 3 is a rear elevation of the portable crane illustrated in Fig. 1.

Fig. 4 is a plan view of the portable crane illustrated in Fig. 1.

I claim:

The ornamental design for a portable crane or similar article, as shown.

LAD L. HERCIK.
